DESIGN FOR A XYLOPHONE OR SIMILAR ARTICLE

Arthur Frohman, New York, N. Y.

Application June 25, 1946, Serial No. 131,019

Term of patent 3½ years

(Cl. D56—1)

To all whom it may concern:

Be it known that I, Arthur Frohman, a citizen of United States, residing at New York city, in the county of Kings and State of New York, have invented a new, original, and ornamental Design for a Xylophone or Similar Article, of which the following is a specification, reference being had to the accompanying drawing, forming part thereof.

In the drawing:

Fig. 1 is a front view of a xylophone or similar article, showing my new design;

Fig. 2 is a top plan view thereof;

Fig. 3 is a bottom plan view thereof;

Fig. 4 is an end elevational view thereof; and

Fig. 5 is a cross-sectional view taken on line 5—5 of Fig. 1.

I claim:

The ornamental design for a xylophone or similar article, as shown.

ARTHUR FROHMAN.
